UNITED STATES PATENT OFFICE.

CHARLES HAMILTON PAJEAU, OF EVANSTON, ILLINOIS.

DESIGN FOR A TOY DOLL.

Application filed December 16, 1921. Serial No. 522,934. Term of patent 14 years.

To all whom it may concern:

Be it known that I, CHARLES HAMILTON PAJEAU, a citizen of the United States, residing at Evanston, in the county of Cook and State of Illinois, have invented a new, original, and ornamental Design for a Toy Doll, of which the following is a specification, reference being had to the accompanying drawings, forming part thereof.

The invention relates to a toy doll composed of wooden spheres strung together in semblance of a human figure of abnormal configuration and having its ornamental appearance and pleasing appearance accentuated by coloring the spheres in relatively contrasting colors.

The figure is an elevation of a toy doll, showing my new design.

I claim:

The ornamental design for a toy doll, as shown and described.

CHARLES HAMILTON PAJEAU.
